UNITED STATES PATENT OFFICE.

GEORGE P. PRESBY, OF WEST BRIDGEWATER, MASSACHUSETTS, ASSIGNOR TO BECK-
WITH BOX TOE COMPANY, OF DOVER, NEW HAMPSHIRE, A CORPORATION OF MAINE.

COUNTER-STIFFENER.

1,219,999.

Specification of Letters Patent. Patented Mar. 20, 1917.

Application filed February 5, 1915. Serial No. 6,255.

To all whom it may concern:

Be it known that I, GEORGE P. PRESBY, a citizen of the United States, and resident of West Bridgewater, in the county of 5 Plymouth and State of Massachusetts, have invented certain new and useful Improvements, in Counter-Stiffeners, of which the following is a specification.

This invention relates to counter stiffeners for boots and shoes, and its object is to provide a counter stiffener which may be shaped in conformity to the lasted shoe with greater facility than counter stiffeners commonly used.

15 The characteristic feature of the present invention is that the counter stiffener is made of two different kinds of material, the counter-stiffening portion being made of relatively stiff material such as leather and 20 the portion which forms the heel-seat flange being made of relatively limp absorbent material overlapping and stitched to the counter-stiffening portion. The absorbent material is impregnated with a suitable hard 25 and adhesive stiffening substance which is moisture-proof and which may be readily softened by heat, and the invention contemplates softening the impregnated absorbent material by heat or otherwise prior 30 to molding the device, and performing the molding operation while the absorbent material is soft and comparatively limber. The molding operation may be performed either by molding apparatus before the 35 counter stiffener is assembled with the other elements of a boot or shoe, or it may be molded while soft and while assembled with the other shoe elements. In the latter case, the molding operation will be incidental to 40 the lasting operation; that is to say, if an unmolded but softened counter-stiffener blank be assembled with the other shoe elements, and the shoe lasted in the usual manner, the pulling over and lasting of the 45 shoe will automatically mold the counter stiffener, and the latter will set in the form imparted to it by the lasting operation.

On the accompanying drawings, which illustrate the present invention,—

50 Figure 1 represents an elevation of a counter-stiffener blank.

Fig. 2 represents a perspective view of an unmolded blank curved to permit assembling with the other elements of a shoe.

Fig. 3 represents a perspective view of a 55 molded counter stiffener.

Fig. 4 represents a longitudinal section of the heel portion of a last together with the shoe elements which are assembled for lasting; an unmolded counter-stiffener blank 60 being included and arranged in position to be molded by the lasting operation.

Fig. 5 represents a view similar to Fig. 4 showing the shoe elements as having been lasted, and the counter stiffener as having 65 been molded by such lasting operation.

Fig. 6 represents a cross section on a larger scale of a portion of a welted shoe on the last. The plane of this section is in the vicinity of the plane where the shank and 70 heel portions meet, the forward portion of the counter-stiffening portion being shown caught by the inseam stitches.

The same reference characters indicate the 75 same parts wherever they occur.

The counter stiffener comprises two members 10 and 11 which are lapped with relation to each other, the lapped portions being fastened together by stitches 12. I have shown two rows of such stitches, these rows 80 being substantially parallel to the edges of the lapped portions. The lower edge of the member 10 is indicated at 13 and the upper edge of the member 11 is indicated at 14. In practice, the edge 13 will be arranged 85 substantially contiguous to the edge of the insole 15 and the counter stiffener will preferably be arranged so that the lapped portion of 11 will be outside of the portion 10.

The member 10 is composed of any suitable stiff material, such as leather, and the member 11 is composed of a limp absorbent material such as wool felt and is impregnated with suitable moisture-proof stiffening substance which at ordinary temperatures will be comparatively hard, but which is capable of being rendered soft and plastic by a moderate degree of heat.

The stiffening substance, which I have found to be satisfactory for the purpose, is 100 a hydrocarbon substance known as montan wax, but, in specifying the latter, I do not

limit the scope of my invention to any one substance. Any other substance, having the characteristics hereinbefore described, would serve the purpose. Montan wax may be used alone or it may be blended with a suitable, relatively hard asphalt, which will melt at approximately 225° F. The two hydrocarbons above mentioned may be blended and form an adhesive compound which will melt at 200° F. and will become soft, sticky and pliable at substantially 160° F.

A blank, such as that shown by Fig. 1, may be molded before being assembled with the other elements of a shoe, but, as a preliminary step to performing the molding operation, the blank, or at least the member 11, should be heated or treated with a solvent to soften the stiffening substance. If the member 11 be heated to a temperature of approximately 180° F., the stiffening substance will be softened to such extent that the member 11 will be limber and may be molded with great facility to form a heel-seat flange as indicated at 16 in Fig. 3. If the stiffening substance be permitted to set while the counter stiffener is in the form shown by Fig. 3, the heel-seat portion will retain such form but will not lose all resilience or flexibility.

I have found, however, that a separate molding operation is not necessary, for, if the unmolded blank be treated to soften the member 11 and while soft is assembled with the other elements of the shoe as shown by Fig. 4 and subjected to a lasting operation, the member 11 will conform to the shape of the other lasted elements as shown by Fig. 5, and will become stuck to the said other elements because of the adhesive quality of the impregnating substance therein.

A portion of a last is indicated at 17 and a shoe upper and lining are indicated respectively at 18 and 19. Assuming that the member 11 is limber when assembled as shown by Fig. 4, and that the lasting operation is performed while the member 11 is limber, the member 11 will be molded by the lasting operation, and upon hardening will set in its molded condition, and will stick to the upper 18 and to the lining 19.

One purpose in arranging the lapped marginal portion of the member 10 inside the lapped marginal portion of the member 11 is to guard the visible portion of the lining in the finished shoe from the discoloring effect of the impregnating substance. Another purpose of such arrangement is to keep the tougher material (leather) against the lining of the shoe where the wear occurs as between the wearer's foot and the counter stiffener. Another purpose is to keep the inner surface of the counter stiffener smooth. If the edge 14 of the member

11 were arranged upon the inner side of the member 10, it would come in contact with the lining and would wear away the lining more rapidly. There is still another reason for the arrangement in question. The connection between the members 10 and 11 depends upon the stitches 12. In consequence of arranging the lapped portion of the member 10 upon the inner side of the member 11, the member 11 is bent upon the edge 13 as shown by Figs. 5 and 6, said edge 75 relieving the stitches of some of the stress to which they are subjected when the member 11 is drawn inwardly and when the shoe is expanded by the wearer's foot.

This invention contemplates sewing the 80 inseam while the member 11 is soft. The counter stiffener is long enough to be lapped by a welt strip 20, in the case of a welted shoe. An inseam stitch is indicated at 21. A very serious difficulty attending 85 the manufacture of boots and shoes, especially low shoes and pumps, has been the difficulty of forming a close tight inseam at the points where the counter stiffener is caught by the inseam stitches. The mate- 90 rial of which most counter stiffeners are made is so stiff that it would be impossible to draw, tuck or otherwise form the counter stiffener snugly into the angle formed by the lip 22 and feather 23 of the insole. If 95 the material of the counter stiffener is too stiff, it will bridge across said angle and leave a cavity, causing the shoe to bulge at the sides of the shank and setting the inseam stitches so far out from the lip that, 100 when the outsole is stitched on, the outsole stitches are unduly set out from the lip of the insole. The outsole stitches are thus in a great many cases forced to lie upon or beyond the line upon which the outsole is to 105 be trimmed. These difficulties all grow out of the inability to form a tight inseam where the ends of the counter stiffener are present. It will be readily understood that these difficulties are overcome by my present invention, provided the member 11 is forced 110 into the angle when it is in a soft limber condition. It will also be understood that the ability of the heated member 11 to conform to the angle of the insole applies to "turned" 115 shoes as well as to "welt" shoes. If desired, the insole may be made while the member 11 is soft and pliable and thus insure its being forced into the angle.

Having thus explained the nature of my 120 said invention, and described a way of making and using the same, although without attempting to set forth all of the forms in which it may be made or all of the modes of its use, what I claim is:—

A counter stiffener comprising a counter member, a heel-seat member composed of absorbent sheet material impregnated with

a stiffening moisture-proof adhesive substance, whereby it is rendered relatively stiff at ordinary atmospheric temperatures but becomes limp and pliable with the application of a moderate degree of heat, said heel-seat member having a heel-seat flange and an upstanding flange adjoining the outer marginal portion of said heel-seat flange, the lower marginal portion of said counter member being arranged inside and

in lapped relation to said upstanding flange, and fastening means arranged to connect the portions so apped.

In testimony whereof I have affixed my signature, in presence of two witnesses.

GEORGE P. PRESBY.
